DESIGN FOR A TRIPOD HEAD FOR A
CAMERA OR SIMILAR ARTICLE

Stanley Flesch, Chicago, Ill.

Application February 3, 1949, Serial No. 647

Term of patent 3½ years

(Cl. D61—1)

To all whom it may concern:

Be it known that I, Stanley Flesch, a citizen of the United States, residing at Park Lane Apartment Hotel, 2842 Sheridan Road, Chicago, in the county of Cook and State of Illinois, have invented a new, original, and ornamental Design for a Tripod Head for a Camera or Similar Article, of which the following is a specification, reference being had to the accompanying drawing, forming part thereof.

Fig. 1 is a front side elevation of a tripod head for a camera or similar article showing my new design;

Fig. 2 is an end view of the same taken on line 2—2 of Fig. 1;

Fig. 3 is an end view of the same taken on line 3—3 of Fig. 1; and

Fig. 4 is a rear side elevation of same.

I claim:

The ornamental design for a tripod head for a camera or similar article, substantially as shown.
STANLEY FLESCH.
